G. F. HALL

COMBINATION SQUARE, LEVEL, AND RULE ATTACHMENT

Filed Aug. 18, 1921

George F. Hall
INVENTOR.

Braentzel ^{BY} and Richards,
ATTORNEYS.

UNITED STATES PATENT OFFICE.

GEORGE F. HALL, OF NEWARK, NEW JERSEY, ASSIGNOR TO JOHN T. UHL, OF NEWARK, NEW JERSEY.

COMBINATION SQUARE, LEVEL, AND RULE ATTACHMENT.

Application filed August 18, 1921. Serial No. 493,399.

To all whom it may concern:

Be it known that I, GEORGE F. HALL, a citizen of the United States, residing at Newark, in the county of Essex and State of New Jersey, have invented certain new and useful Improvements in Combination Square, Level, and Rule Attachments; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention has reference, generally, to improvements in that class of articles adapted for use by carpenters, draftsmen, and others, as a combined square, bevel, level, and a means for finding centers, as well as for scribing circles and arcs of circles; and, the present invention has reference, more particularly, to a novel and simply constructed combination tool for the above stated and other uses, which is made in the form of an attachment adapted to be readily and quickly mounted in an operative relation to a carpenter's rule, and is just as quickly detached therefrom.

The invention has for its principal objects to provide a novel and simply constructed, as well as an easily manufactured device or tool of the general character hereinafter more fully set forth, the same being readily attachable to and detachable from the ordinary carpenter's rule, to be used as a square, a bevel, and for many other similar uses.

Other objects of the present invention not at this time more particularly enumerated, will be clearly understood from the following detailed description of the present invention.

With the various objects of the present invention in view, the said invention consists, primarily, in the novel and simple compound tool and rule-attachment hereinafter set forth; and, the said invention consists, furthermore, in the novel arrangements and combinations of the various parts thereof, as well as in the details of the construction of the said parts, all of which will be more fully described in the following specifica-

tion, and then finally embodied in the clauses of the claims, which are appended to and which form an essential part of the said specification.

The invention is clearly illustrated in the accompanying drawings, in which:

Figure 1 is a plan view of a combination tool, made according to and embodying the principles of the present invention, the same being shown attached in an operative position to the usual carpenter's rule.

Figure 2 is a similar view of the combination tool, detached from the said rule; Figure 3 is a top-edge view of the same; and Figure 4 is a cross sectional representation of the tool, said section being taken on line 4-4 in said Figure 2, looking in the direction of the arrow x.

Similar characters of reference are employed in the above described views, to indicate corresponding parts.

Referring now to Figures 1 to 4 inclusive, the reference-character 1 indicates a complete combination tool or rule-attachment, showing one embodiment of the principles of the present invention, the device, in general, being of a triangular configuration, as shown more particularly in Figure 2, comprising a base member consisting of an arrangement of lower bars or members 2 and 3, and the intermediate connecting members 4 and 5, arranged at 45 degrees to said members 2 and 3, so as to provide an angle of 90 degrees between the members 4 and 5. At the ends of the respective members 2 and 3, are right-angled members 6 and 7, from which extend the members 8 and 9, meeting in a point, as at 10, said members 8 and 9 being also disposed at 45 degrees to the plane of the lower faces of said bars or members 2 and 3. At the joint 10 of the members 8 and 9 is a suitably pointed pivot-point or centering pin 11, and connecting the said members 8 and 9 is a body-portion 12, having a laterally extending tubular portion for the securing therein of a level, as 13, which is partially exposed, for reading purposes, above a curved or arc-shaped portion 114 of the said body-member 12. Extending from the lower marginal surface-portion of said body-member 12, and respectively connected with the members 2, 4, 5 and 3, are other

members 14, 15 and 16, said latter members being respectively provided with alined circular holes, as 17, 18 and 19, forming bearing-guides for movably mounting therein a 5 stem or rod 20. Secured to one end of said stem or rod 20, by means of a screw 21, or otherwise, is a plate 22, said plate normally resting against the outer face 23 of the member 14, and being provided with 10 a forwardly extending portion, as 24, from which extends at a right-angle, a clamping lug or member 25, said lug or member 25 extending into and from a suitably formed guiding opening or hole 27, in a projection 15 26 with which the member 14 is provided upon its upper surface, as will be seen from an inspection of said Figure 2 of the drawings. At its opposite end, the said stem or rod 20 has a screw-threaded part 28, 20 upon which is adjustably disposed an internally screw-threaded sleeve or nut 29, the slotted end of which is adapted to receive a screw-driver, for its proper adjustment upon the screw-threaded portion of 25 the stem or rod 20, being suitably disposed in a hole or opening 30, with which the member 5 is provided. Encircling the said stem or rod 20, between the member 16 and the end of said sleeve or nut 29 is a 30 coil-spring 31, the initial tendency of which is to force the said stem or rod 20, and the clamping lug or member 25 in the direction indicated by the arrow α , shown in Figure 2 of the drawings. As shown, the said member 35 9 is provided with a retaining guide-lug or projection 32, and in alinement with said guide-lug or projection 32, at the junction of the members 3 and 5 is another guide-lug 33, between which two guide-lugs 40 and the end of the clamping lug 25, a folded carpenter's rule, as 34, can be forcibly sprung, as will be evident, and suitably held by frictional holding engagement, as will be fully understood from an inspection of 45 said Figure 1 of the drawings.

The manner of securing the combination tool to the carpenter's rule will be readily seen from an inspection of the several figures of the drawings; and, the manner of 50 employing the attachment as a square, a bevel, a level, as well as for scribing circles, and arcs of circles, will be readily understood, and any further description of the same is therefore deemed unnecessary.

55 Of course I am aware that some changes may be made in the general arrangements and combinations of the several devices and parts, as well as in the details of the construction of the same, without departing 50 from the scope of the present invention as set forth in the foregoing specification, and as defined in the clauses of the claims which are appended thereto. Hence, I do not limit my present invention to the exact arrangements and combinations of the various

devices and parts as described in the said specification, nor do I confine myself to the exact details of the construction of the said parts, as illustrated in the accompanying drawings.

70

I claim:

1. A combination tool of the character set forth, comprising a base member and side-members disposed at an angle to said base-member, and a rule-attaching means 75 consisting of a projection extending at a right angle from one of the faces of said base-member and adapted to engage one edge of the rule, and a spring-controlled clamping stem slidably disposed within said base-member and adapted to engage the opposite edge of the rule, and means connected with said stem for adjustment of said spring-controlled stem.

2. A combination tool of the character 85 set forth, comprising a base-member and side-members disposed at an angle to said base-member, and a rule-attaching means consisting of a projection extending at a right angle from one of the faces of said 90 base-member and adapted to engage one edge of the rule, a spring-controlled clamping stem slidably disposed within said base member and adapted to engage the opposite edge of the rule, said stem being provided with a screw-threaded portion, and an adjusting nut mounted upon said screw-threaded portion.

3. The herein described rule-attachment 100 in the form of a triangularly shaped main body comprising a base-member and side-members disposed at an angle to said base-member, a connecting member disposed between said side-members, a level imbedded in said connecting member, said connecting member having a curved portion for partially exposing a part of the level, guide-members between said connecting member and said base-member, rule-engaging retaining lugs extending at right angles from 110 one of the faces of said body, and a spring-controlled rule-engaging clamping stem movably mounted in said guide-members.

4. The herein described rule-attachment 115 in the form of a triangularly shaped main body comprising a base-member and side-members disposed at an angle to said base-member, a connecting member disposed between said side-members, a level imbedded in said connecting member, said connecting member having a curved portion for partially exposing a part of the level, guide-members between said connecting member and said base-member, rule-engaging retaining lugs extending from said body, and a rule-engaging clamping stem movably mounted in said guide-members, said stem having a screw-threaded end-portion, a coil-spring encircling said stem, and a threaded adjusting nut upon the screw- 125 130

threaded end-portion of said stem in engagement with said spring for adjustment of the same.

5. The herein described rule-attachment in the form of a triangularly shaped main body comprising a base-member, and side-members disposed at an angle to said base-member, a connecting member disposed between said side-members, a level imbedded 10 in said connecting member, said connecting member having a curved portion for partially exposing a part of the level, guide-members between said connecting member and said base-member, rule-engaging lugs 15 extending from said body, and a guide-provided lug extending from one of said guide-members, a stem movably disposed in said

guide-members, a plate at one end of said stem, and a rule-engaging clamping lug extending from said plate into and through 20 said guide-provided lug for engagement with the rule, said stem being provided with a screw-threaded portion, an adjusting nut mounted upon said screw-threaded portion of the stem, and a coil-spring upon said stem 25 between one of said guide-members and the said nut.

In testimony that I claim the invention set forth above I have hereunto set my hand this 15th day of August, 1921.

GEORGE F. HALL.
